UNITED STATES PATENT OFFICE.

GEORGE CLARK, OF WEST TROY, NEW YORK.

STEAM-RADIATOR.

SPECIFICATION forming part of Letters Patent No. 237,819, dated February 15, 1881.

Application filed July 8, 1880. (No model.)

To all whom it may concern:

Be it known that I, GEORGE CLARK, a citizen of the United States, residing at West Troy, in the county of Albany, and State of New York, have invented new and useful Improvements in Steam-Radiators, of which the following is a specification.

My invention relates to certain new and useful improvements in steam-radiators. It has for its object to produce a more thorough circulation of the cold air to be heated; and it consists in the arrangement of the steam-pipes in two piles with a space between them to form a flue, said flue being so divided horizontally as to form a series of air-heating chambers at different altitudes, and adapted to receive and expel the air to be heated, as will be herein-after more fully set forth.

In order that those skilled may fully understand my invention, I will proceed to describe the same, referring by letters to the accompanying drawing, which represents a central cross-section of a steam-radiator embodying my invention.

A A are the steam-pipes or side plates, having the outward appearance of corrugated plates, through which the steam is caused to circulate in the usual manner, being received and discharged through pipes shown in dotted lines. The corrugated plates or tubes are formed in couplets with thin webs B B' B B', &c., so that when they are arranged in the usual way a short distance apart a vertical space is left between them, and when the ends are surrounded by a solid plate, C, said space has no communication with the outside air, except as hereinafter explained. These side plates, formed as described, are mounted upon a suitable base, D, and surmounted with a cap, E. The webs B' are somewhat longer (vertically) than the webs B, in order that they may be perforated, as shown by the horizontal arrows, without weakening them too much. At the points B' there are cast or otherwise formed with the webs horizontal plates F, extending inwardly to the center of the space between the two side walls, and outwardly a short distance only, to form a deflecting-plate at such point. The inwardly-projecting portions, when the sides of the radiator are in position, firmly abut to form a continuous par-

tition, thus forming compartments G, the number of such compartments depending upon the location and number of plates F, in which particular I do not wish to limit my invention. 55 These plates may simply abut, as described, or they may overlap, as shown at a, in the top partition.

It will be observed that the perforations through the webs B' are below and above the plates F, so that the lower one forms the exit from one compartment, G and the upper one the inlet to the next compartment above.

The lowest or foundation steam-pipe may be cast with a web, B'', designed to rest in a suitable groove in the bottom or base plate, D, and by which it may be held in position, and the upper tier of pipes and the cap-plate E may be similarly connected.

The lowermost web, B'', may be perforated 70 to receive the strata of cold air nearest to the floor, or the plate D may be perforated, as seen at b b, and the cap-piece E should be perforated or cast open for final exit.

The inlets and exits to the several compartments are composed of a series of perforations, so that the air is divided up into a series of fine streams, as I have found that this greatly facilitates the heating of the same.

From the construction described it will be 80 seen that the cold air at different altitudes in a room is drawn in at the bottom of each heating-compartment G, and in its travel upward is heated by radiation and escapes at the top of said chamber or compartment, the 85 outwardly-projecting portions of the plates F serving to direct it horizontally into the room.

It will be observed that if the compartments G were formed into a single flue by the removal of the plates F, and the perforations 90 at B' dispensed with, the result would be a single continuous flue, into which the cold air would be drawn at the bottom only and rapidly discharged at the top without becoming thoroughly heated. By dividing up this space 95 and providing for the entrance of cold air at different altitudes a much better result is accomplished.

I do not wish to confine myself to the exact details of construction, as they may be considerably varied without departing from the spirit of my invention, the gist of which rests

in the idea of forming a series of air-heating compartments at different altitudes.

What I therefore claim as new, and desire to secure by Letters Patent, is—

5. 1. A steam-heating radiator composed of pipes or steam-conduits having the outward appearance of corrugated plates, with web-like connections, and provided at one or more points with plates F, whereby two or more compartments G are formed, substantially as and for the purpose set forth.

10. 2. The webs B', perforated above and below

the plates F, substantially as and for the purpose set forth.

15. 3. The plates F, extending externally a short distance to form deflectors, as hereinbefore set forth.

In testimony whereof I have hereunto set my hand and seal in the presence of two subscribing witnesses.

GEORGE CLARK. [L. S.]
